UNITED STATES PATENT OFFICE.

GUSTAVE LIDSEEN, OF CHICAGO, ILLINOIS.

OIL-CAN LEVER MECHANISM.

1,346,130.

Specification of Letters Patent. Patented July 13, 1920.

Application filed June 28, 1917. Serial No. 177,448.

To all whom it may concern:

Be it known that I, GUSTAVE LIDSEEN, a citizen of the United States, and a resident of the city of Chicago, in the county 5 of Cook and State of Illinois, have invented certain new and useful Improvements in Oil-Can Lever Mechanism; and I do hereby declare that the following is a full, clear, and exact description of the same, reference 10 being had to the accompanying drawings, and to the numerals of reference marked thereon, which form a part of this specification.

This invention relates to an improved 15 form of an oil can having a lever operated ejecting mechanism mounted within the oil can cap to force oil out of the oil can under direct pressure, said lever projects through the cap of the oil can and is held in operating position against the action of a controlling spring of the ejecting 20 mechanism by a guide clip engaging the lever and inner surface of said cap.

It is an object of this invention to construct an oil can having a lever operated 25 ejecting mechanism in the cap thereof for forcing oil from the spout of the can under pressure, said lever having a retaining clip engaged on the inner end thereof to hold 30 the lever in an operating position and prevent leakage through a slot in said cap through which the lever projects.

It is also an object of this invention to construct a lever operated oil can, the lever 35 of which has a clip engaged on the inner end thereof to prevent leakage and hold said lever in an operating position.

It is furthermore an object of this invention to provide an oil can provided with a 40 lever projecting through a slot in an indented portion of the cap of the oil can, said lever having a retaining member clamped on the inner end thereof which slidably engages said indented portion of 45 the cap to hold said lever in an operating position and prevent leakage through said slot.

It is an important object of this invention to provide an oil can simple and effective 50 in construction, wherein a means connected with the cap of the oil can is used to prevent leakage and to hold the operating parts in position.

Other and further important objects of 55 the invention will be apparent from the

disclosures in the drawings and specification.

The invention (in a preferred form) is illustrated in the drawings and hereinafter more fully described.

60

On the drawings:

Figure 1 is a side elevational view of an oil can equipped with a lever mechanism embodying the principles of my invention.

Fig. 2 is an enlarged fragmentary top 65 plan view of the oil can with the cap removed.

Fig. 3 is an enlarged bottom plan view of the oil can top, removed from the can.

Fig. 4 is an enlarged section taken on 70 line 4—4, of Fig. 3, with parts broken away and with parts shown in elevation.

Fig. 5 is a similar section with the lever depressed to show the operation of the pump mechanism.

Fig. 6 is a section taken on line 6—6, of Fig. 4.

Fig. 7 is central vertical section of the plunger cup of the pump mechanism.

As shown on the drawings:

The reference numeral 1, designates a can, body portion or container, the upper end of which is rounded or tapered inwardly to connect with an integral neck 2, the upper margin of which is bent outwardly at right 85 angles to afford a flange 3, having integrally formed on opposite sides thereof, by cutting away portions of the flange, curved or arc shaped ears or lugs 4, one end of each of which is in the plane of the flange 3, 90 while the other end, denoted by the numeral 5, is deflected downwardly. The ears 4, are disposed with the like ends thereof positioned diametrically opposite one another, as clearly shown in Fig. 2.

Removably engaged upon the can 1, is a spout cap comprising a cylindrical casing or cap 6, to the upper end of which is rigidly secured by soldering or other suitable means, a centrally passaged outwardly tapering 100 spout or nozzle 7. Integrally formed at right angles to the lower end of the cap 6, is a cover plate 8, the margin of which is bent downwardly at right angles and then inwardly to afford an inner peripheral 105 groove and an integral flange 9. The flange 9, has portions thereof cut away to form oppositely disposed ears or lugs 10, one end of each of which lies in the plane of the flange 9, while the other end of each there- 110

of is bent outwardly or deflected as denoted by the numeral 11. The ends of the ears 10, are arranged with the like ends thereof disposed diametrically opposite one another 5 as shown in Fig. 3. Removably seated within the inner peripheral groove of the cover plate 8, is a washer or packing ring 12, made of rubber or any other suitable material.

Slidably mounted within the cylindrical 10 cap 6, is an oil ejecting mechanism comprising a plunger or cup 13, having portions on opposite sides thereof cut away to provide outlet openings 14, to permit oil from the can 1, to pass therethrough into the 15 spout 7, of the oil can, when the same is inverted for use. Positioned within the plunger 13, with its lower end seated upon the inner surface of the base of the plunger, is a spiral spring 15, which controls the 20 operation of the plunger and has its upper end contacting the inner surface of a shoulder 16, formed at the upper end of the cap 6, for the purpose. To hold the ejecting mechanism parts in position to permit actuation 25 of the same, the inner end of a curved actuating or supporting arm 17, contacts the bottom surface of the plunger 13, while the outer end thereof is curved upwardly and projects through a slot 18, provided in an 30 indented portion or socket 19, formed by depressing a portion of the cover plate 8, at one side of the cap 6. Movably seated within the socket 19, to cover the slot 18, and afford a non-leaking joint, is a curved 35 plate 20, having an aperture therein through which the outer end of the arm 17, projects after passing through the slot 18. Integrally formed on the outer end of the arm 17, is an enlarged finger piece or lever 21, 40 of a width equal to the length of the curved plate 20, and having the inner end thereof adjacent the plate 20, curved to conform to the curvature of said plate, while the outer end of the lever is bent at an angle to the 45 curved portion thereof to contact the outer edge of said curved plate 20, to permit actuation thereof in the socket 19, when the lever is actuated.

To hold the curved plate 20, seated in the 50 socket 19, the outer end of the arm 17, is soldered or rigidly secured by other suitable means to said plate 20, to close the aperture therein and form a unitary mechanism. Leakage of oil through the slot 18, of the 55 socket 19, is prevented by means of a washer, retaining clip or guide clip, one end of which comprises a head 22, curved to contact and conform to the curvature of the inner surface of the socket 19, and having 60 an aperture therein through which the outer end of the curved arm 17, projects. Integrally formed on the inner end of the head 22, is a curved shank 23, which lies upon the upper curved surface of the arm 65 17, and is tapered to extend to a point about

half way between the ends of said arm 17, and has integrally formed on each side of the narrow or inner end thereof a lug 24, which is bent downwardly at right angles to grip the sides of the arm 17, to hold the 70 retaining clip clamped in position thereon for the purpose of holding the rigidly connected curved plate 20, and the lever 21, seated in the socket 19, against the action of the spring 15, to prevent leakage of oil 75 out through the slot 18, when the oil can is inverted for operation.

The operation is as follows:

When it is desired to use the oil can the top is removed and the can 1, is filled with 80 oil. To replace the oil can top which comprises the cover plate 8, the cap 6, spout 7, and the ejecting mechanism, the cover plate 8, is placed with its flange 9, resting upon the can flange 3, and with the cover plate 85 ears 10, registering with the cut-out portions of the flange 3. The deflected ear portions 11, are disposed adjacent the raised portions of the ears 4, in which position the cover plate 8, is given a quarter turn in a 90 clockwise direction to permit the ears 10, to slidably engage below the ears 4, to frictionally hold the top in position upon the can 1, with the packing 12, pressing upon the flange 3, to afford an air-tight fit. 95

To use the oil can the same is turned to one side or inverted with the mouth of the spout 7, engaged in or upon a device requiring lubrication, in which position the oil in the can flows through the openings 14, into 100 the cap 6. The lever 21, is now depressed, rotating or moving the curved plate 20, in the socket 19, and also thereby moving the outer end of the arm 17, in the slot 18, simultaneously raising the inner end of said arm, thus forcing the plunger cup, 13, into the cylindrical cap 6, against the action of the spring 15, which is compressed as shown in Fig. 5. By the above operation of the 105 ejecting mechanism, the oil in the cap 6, is entrapped and forced out of the mouth of the spout 7, under direct pressure independently of any flexing of the sides or bottom of the oil can. 110

The curved plate 20, which is rigidly secured to the lever 21, is held seated in the socket 19, by the retaining clip which is clamped upon the arm 17, which engages through the apertured head 22, the curvature of which permits the same to slidably 115 engage the inner surface of the socket 19, and thus act as a guide and a retaining means for the lever mechanism, and also preventing leakage of oil through the slot 18. 120

I am aware that various details of construction may be varied through a wide range without departing from the principles of this invention, and I therefore do not purpose limiting the patent granted otherwise than necessitated by the prior art. 125 130

I claim as my invention:

1. The combination with a socket member having a slot therein, a lever projecting through said slot, and apertured members engaged on the exterior and interior portions of said lever and co-acting with said slotted member to hold the lever fulcrumed in operating position.
2. The combination with a plate, of a slotted socket formed therein, a curved apertured plate movably seated in said socket, a lever projecting through said curved plate and through said slotted socket, a retaining clip clamped on the inner portion of said lever and contacting said socket for holding the lever in a fulcrumed position, and lugs integrally formed on said clip and engaged around said lever to hold the clip in position.
3. In a device of the class described the

combination with a slotted socket, of a curved plate seated in said socket to cover the slot therein, a curved arm projecting through said slotted socket and curved plate, a lever integrally formed on the outer end 25 of said curved arm and formed to seat in said curved plate, said lever adapted when actuated to move said curved arm and plate, and a retaining member clamped on said curved arm and engaging the under surface 30 of said socket to hold the curved plate and lever seated within said socket.

In testimony whereof I have hereunto subscribed my name in the presence of two subscribing witnesses.

GUSTAVE LIDSEEN.
